DIRECTIONAL AERIAL

Pierre Paul Gamet, Paris, France; vested in the
Alien Property CustodianApplication August 19, 1942, Serial No. 455,378
In France August 20, 1941

9 Claims. (Cl. 250—33)

The present invention relates to a directional aerial without a reflector as used for transmitting or receiving more particularly short or very short or even ultra-short waves by means of conductors traversed by progressive waves.

For this purpose it is known to provide aerials with four radiating elements or strands arranged in the form of a lozenge, two of the said radiating strands being connected each to a wire of the bipolar feeder while the two other radiating strands are connected with an impedance the value of which is equal to the characteristic impedance so as to avoid wave reflections.

The aerials of this type offer various drawbacks and more particularly the following:

The radiating diagrams of the said aerials comprise secondary follicles which radiate in a prejudicial direction; for this reason these follicles are troublesome and diminish the energy transmitted by the aerial in the preferred selected direction.

On the other hand it is very difficult to obtain a radiating beam making a very small angle with the horizontal line in a vertical plane.

The present invention has more particularly for its object to remedy the said drawbacks in a certain measure and to reduce the secondary radiating follicles so as to insure a higher energy in the preferred selected direction.

An improved directional aerial permitting to attain the above mentioned objects presents the characteristic features which appear from the following description and more particularly from the appended claims.

Aerials according to the invention are shown by way of examples in the appended drawings in which:

Figure 1 is a diagrammatic representation showing the elements of my aerial with its feeding system.

Figure 2 is a diagram of the aerial showing the direction of the currents flowing through the various conductors.

Figure 3 is a diagrammatic perspective view of my aerial.

Figure 4 is a three-dimensional polar radiation diagram of the aerial.

Figure 5 is a two-dimensional polar radiation diagram in a horizontal plane.

Figure 6 is a two-dimensional polar radiation diagram in a vertical plane. 50

Figures 7 and 8 show diagrammatically two forms of embodiment of the invention.

Figure 9 shows diagrammatically a composite array or net of aerials according to the present invention. 55

Figure 10 shows another composite array or net of aerials according to the present invention.

The aerial of the present invention (see Figures 1 to 3) is formed of a conductor 7, 8 serially

followed by a conductor 8, 9 itself serially followed in turn by a conductor 9, 10. To the end 10 of this latter conductor is connected a terminating impedance 11 which is equal to the characteristic impedance of the aerial.

At the other end 12 of the said impedance is connected another conductor 12, 13, serially followed by a conductor 13, 14, which is itself followed serially in turn by a conductor 14, 15.

10 All these conductors may have any length, but this length is generally equal to a wave length or to a multiple of the wave length.

The array of the said conductors with the characteristic terminating impedance 11 forms a broken line having the form of a convex regular hexagon the extremities 7 and 15 of which are connected to the conductors 16 and 17 of a bipolar feeder which connects the said aerial with the high-frequency generator 18.

20 This aerial operates in the following manner:

The generator 18 (see Figure 1) delivers high-frequency energy to the feeder 16, 17, the characteristic impedance of which is equal to the impedance presented by the aerial between the points 7 and 15. Thus, the attack of the aerial between the said two points in no way modifies the operating conditions of the feeder.

The free end of this aerial 7 and 15 is closed across an impedance 11 which is a pure ohmic impedance equal to the characteristic impedance of the system.

Under these conditions the aerial can be compared with a line of infinite length since at every point of this line the value of the impedance is always equal to the characteristic impedance.

Let 19 be a point of the aerial located at a distance x from the point 7.

In such a system the propagation is of the form $E = E_0 e^{-Px}$ where P is the propagation constant and B an amplitude coefficient.

If E_0 and I_0 represent the voltage and the current respectively at the point of output and if I and V represent these same values respectively at a point of the line located at a distance X from the origin, one has

$$P = \alpha + j\beta \quad (1)$$

where α is the damping constant and β the phase constant or

$$\frac{2\pi}{\lambda}$$

$$V = E_0 e^{-Px} = E_0 e^{-\alpha x} e^{-j\beta x}$$

but

$$e^{-j\beta x} = \cos \beta x - j \sin \beta x$$

The current and the voltage are of the form:

$$V = E_0 e^{-\alpha x} [\cos \beta x - j \sin \beta x] \quad (2)$$

$$I = I_0 e^{-\alpha x} [\cos \beta x - j \sin \beta x]$$

60 the moduli of which are $E_0 e^{-\alpha x}$ and $I_0 e^{-\alpha x}$.

The value of the current I_1 which flows through the conductor 7, 8, is given to a first approximation by neglecting the damping within the limits where the term $e^{-\alpha x}$ can be considered as constant in the following expression:

$$I_1 = A \sin 2\pi \left[\frac{t}{T} - \frac{x}{\lambda} \right] \quad (3)$$

where T is the period or cycle, t the time and λ the wave length.

Such a wave is a progressive wave characterized by an amplitude the effective value of which regularly decreases along the line and the phase of which varies linearly with the distance.

The currents which flow through the aerial will thus have the direction indicated by the arrows in Figure 1.

A calculation effected by means of Formulae 2 shows that the currents which flow through the elements of the aerial can be considered as fairly equal, the term $e^{-\alpha x}$ remaining fairly constant, and that one has

$$I_1 \approx I_2 \approx I_3 \approx I_4 \approx I_5 \approx I_6$$

for aerials of usual dimensions. The field E produced by the currents I_2 and I_5 at a point M (see Figure 3) of zenith distance θ and of a co-latitude ϕ is of the form:

$$E = K_1 I_2 \left[\frac{\cos \left[\frac{\pi}{2} \sin \theta \sin \phi' \right]}{\sqrt{1 - \sin^2 \theta' \sin^2 \phi'}} - \sin \left[2 \frac{\pi H}{\lambda} \cos \theta' \right] \right] \\ - K_2 I_5 \left[\frac{\cos \left[\frac{\pi}{2} \sin \theta \sin \phi \right]}{\sqrt{1 \sin^2 \theta \sin^2 \phi}} - \sin \left[2 \frac{\pi H}{\lambda} \cos \theta \right] \right]$$

(where K_1 and K_2 are two constants and where H is the effective height of an element).

The same would be true for the current elements I_3 and I_6 or I_1 and I_4 the effect of which would appear as the cosine of the angle which they make with the elements I_2 and I_5 .

If the point M is located in a plane perpendicular to the axis x' one will have $\phi=0$ and the preceding equation will be reduced to

$$E = K_1 I_2 \sin \left[2 \frac{\pi H}{\lambda} \cos \theta \right] - K_2 I_5 \sin \left[2 \frac{\pi H}{\lambda} \cos \theta \right]$$

If the point M is located at a comparatively great distance from the aerial one will have very nearly $K_1 I_2 = K_2 I_5$, and $\theta = \theta'$.

Accordingly, for all the points located in a plane perpendicular to the axis x x' (i. e. the axis A A' in Figure 2) the resulting radiation is nearly nil.

The same is true for the axes B B' and D D'. On the contrary, there is adding of the fields in the direction C C' and thus a maximum radiation and no field at all in the direction C C'.

The form of the radiation in space is shown in Figure 4.

The plane 20 of the aerial being horizontal, the radiation takes place in this plane in the direction 21—22.

The maximum radiation angle in the vertical plane is shown by γ .

Figures 5 and 6 show the polar radiation diagrams in the horizontal and in the vertical plane respectively.

In the horizontal plane about the radiation curve 23 there remain secondary follicles 24, 25, 26, 27, 28 radiating in undesired directions. But these follicles have only a small amplitude with respect to the radiation curve 23 and are considerably reduced with respect to those of the radiation diagrams of the aerials.

In the vertical plane the radiation curve 29 is

inclined above the ground along an angle γ which can be very small (5° in the case of Figure 6).

The secondary radiation follicles 32, 33, 34 have a small amplitude and consequently offer negligible difficulty.

Moreover, the value of the radiation angle as well as the width of the beam can be modified by adjusting:

- 10 (1) The height of the plane of the aerial above the ground;
- (2) The length of the sides of the hexagon;
- (3) The angles which the sides of the hexagon make with one another.

15 It is easy to increase considerably the field in the preferred direction (while reducing the secondary follicles) by giving the sides of the hexagon values which are greater than two wave lengths or three wave lengths.

20 In this manner it is easy to obtain considerable gains of the order of 15, 20 and even 25 decibels in the preferred direction through the circular radiation which would be produced by a dipole energized under the same conditions.

25 This aerial which has been described offers numerous advantages and more particularly the following ones:

30 (1) First it has an excellent efficiency since the prejudicial radiations represented by the secondary follicles are considerably reduced.

35 (2) It is also very easy to modify the angle of inclination and the acuteness of the radiating beam and to obtain radiating diagrams showing great symmetry.

40 (3) The aerial has a fairly high aperiodicity, which permits to use it in devices with wide pass bands (transmission and reception of images in television).

45 Numerous changes and modifications can be made in the above described device without departing from the scope and spirit of my invention.

The directional aerial can have the form of an irregular convex hexagon (Figs. 7 and 8) provided, however, that it has a perfectly symmetrical form with respect to the axes x x' (Figures 7 and 8), that is to say that the sides 41, 42, 43 respectively must be parallel to the sides 44, 45, 46 respectively.

50 More particularly, the conductors 42 and 45 (Fig. 7) can be made longer than the other conductors 41, 43, 44 and 46.

The said conductors 42 and 45 can also be made shorter than the other conductors 41, 43, 44 and 46 (Figure 8).

55 The sides of these hexagons may have any length whatever.

The present invention also covers nets or arrays formed by the grouping of a plurality of the preceding aerials and permitting to obtain either a better directional efficiency or a better power efficiency.

60 The net or array shown in Figure 9 is formed of four hexagonal aerials 51, 52, 53 and 54 arranged symmetrically around the point 60 so that the axes E E' and F F' of the said aerial are perpendicular.

65 Each of these aerials is closed across a characteristic impedance 55, 56, 57, 58.

The hexagonal aerials 51, 52, 53 and 54 are connected with one another in the following manner:

70 The output conductor 61 of the hexagonal aerial 51 is connected with the input conductor 67 of the hexagonal aerial 52; the output conductor 63 of the aerial 52 is connected with the input

conductor of the hexagonal aerial 53 and so on, the output conductor 67 of the last aerial 54 being connected with the input conductor of the first aerial 51.

The conductors which are connected together in this manner can form a single conductor, each of the conductor units 61 and 62, 63 and 64, 65 and 66, 67 and 68 having elements in common.

This arrangement offers the advantage that it permits to obtain a very sharp directional radiation.

It is used effectively in radio beacon systems.

It is also possible to arrange aerials in a row (Figure 10) by replacing the characteristic impedance of a first aerial by a second aerial the characteristic impedance of which is also replaced by a third aerial and so on.

Thus a series of aerials 36, 37, 38 (Fig. 10) is obtained which are connected in series, the first (36) of the said aerials receiving across its input terminals the energy supplied by the generator 18 through the wires 16 and 17 of the feeder and the last (38) of the said aerials being closed across its characteristic impedance 11.

This arrangement offers the advantage of diminishing the losses of energy in the terminal impedance since the first aerial instead of delivering into a non-radiating impedance delivers into a second radiating aerial which in its turn delivers into a third aerial and so on.

I claim:

1. In a directional aerial for transmitting or receiving electro-magnetic waves, three rectilinear radiating conductors connected in series, three other rectilinear radiating conductors connected in series, an impedance connecting an adjacent pair of free ends of each unit of three conductors and thus forming a convex hexagon, both these units of three conductors each and this impedance being arranged symmetrically with respect to an axis passing through the input into the aerial across the other adjacent pair of free terminals, and a feeding device connected with this hexagon.

2. In a directional aerial for transmitting or receiving electro-magnetic waves, three equal radiating conductors connected in series and making equal angles with one another, three other radiating conductors equal to one another and to the first three conductors and also making equal angles with one another, an impedance connecting together with each other each said unit of three conductors and thus forming a regular hexagon, and a feeding device connected with said hexagon.

3. In a directional aerial net, a first hexagonal aerial according to claim 2 a second hexagonal aerial the input of which is connected to the output of the first hexagonal aerial, a third hexagonal aerial the input of which is connected with the output of the second hexagonal aerial, a last hexagonal aerial the input of which is connected with the output of the preceding hexagonal aerial while its output is connected to the input of the first hexagonal aerial and a feeding device connected with said net.

4. In a directional aerial net, a first hexagonal aerial, a second hexagonal aerial identical to the first aerial and the axis of which is perpendicular to the axis of the first aerial, the input of this second aerial being connected with the output of the first hexagonal aerial, a third hexagonal identical aerial the axis of which coincides with the axis of the first aerial and the input of which is connected with the output of the second hex-

agonal aerial, a fourth hexagonal identical aerial the axis of which coincides with the axis of the third aerial and the input of which is connected with the output of the third aerial while its output is connected with the input of the first aerial, and a feeding device connected with said net.

5. In a directional aerial net, a first hexagonal aerial, a second hexagonal aerial mounted in the place of the impedance of the first hexagonal aerial, a third hexagonal aerial mounted in the place of the impedance of the second hexagonal aerial, a last hexagonal aerial mounted in the place of the impedance of the last but one hexagonal aerial, and a feeding device connected with said net.

6. In a directional aerial, an array of two groups each of three conductor elements and arranged substantially in the form of a hexagon with one element of each group substantially parallel to an element of the other group, a terminating impedance connected between the adjacent terminals of each of said groups at one end of said array and of value equal to the characteristic impedance of said array, and a high-frequency source connected across the adjacent terminals of each of said groups at the opposite end of said array, said elements being arranged symmetrically about an axis passing through said source and said impedance.

7. An aerial as set forth in claim 6, said elements being of equal length and their array substantially constituting a regular hexagon.

8. In an aerial, a ring array of a plurality of an even number of antenna units, each of said units consisting of two groups each having three conductor elements connected in series, the elements of a said unit being arranged substantially in the form of a hexagon with one element of each group substantially parallel to an element of the other said group thereof, each said unit having a terminating impedance connected across the adjacent terminals of each of its said groups at one end of said unit and of value equal to the characteristic impedance of said unit, said units being arranged in a ring array with impedances on the outside of said ring and with the element of each group of each unit near the center of said ring, at the end thereof opposite its said impedance, being electrically in common with the adjacent element of the adjacent unit near the center of said ring and at the end thereof opposite the impedance of said adjacent unit.

9. In an aerial, a row array of a plurality of antenna units, each of said units consisting of two groups each having three conductor elements connected in series, the elements of a said unit being arranged substantially in the form of a hexagon with one element of each group sub-

stantially parallel to an element of the other said group thereof, a final one of said units having a terminating impedance connected across the adjacent terminals of each of its said groups at one end of said unit and of value equal to the characteristic impedance of said final unit, said units being arranged in a row with said final unit at one end thereof, and with the adjacent terminals of each group of adjacent units being connected together, the impedance of each said unit being equal to the characteristic impedance of the preceding unit more remote from said final unit,

and a high-frequency source connected to the free terminals of the groups of the initial one of said units most remote from said final unit.

PIERRE PAUL GAMET.
